UNITED STATES PATENT OFFICE

CARL L. IPSEN AND ALBERT N. OTIS, OF SCHENECTADY, NEW YORK, ASSIGNEES TO
GENERAL ELECTRIC COMPANY, A CORPORATION OF NEW YORK

FURNACE

Application filed May 6, 1931. Serial No. 535,412.

Our invention relates to furnaces, more particularly to annealing furnaces and has for its object the provision of means whereby a predetermined cooling cycle may be obtained.

In certain heating operations, especially in the annealing of metals, it is often permissible to cool the charge at a more rapid rate than the natural cooling rate of the furnace when 10 shut down, particularly after the charge has cooled down at the natural rate to a predetermined temperature, depending on the material being treated. It is, of course, desirable to decrease the cooling period to the 15 shortest possible time consistent with the requirements of the material, in order to increase the output of the furnace. Many of the alloy steels are very sensitive to exposure to air at high temperature, detrimental 20 carburization taking place under these conditions which may impair the material, and they are also sensitive to cooling at a too rapid rate since this may harden or stiffen the material, making it difficult to machine, form 25 or otherwise manipulate. In general, certain steels must be cooled at a fairly slow rate until they are below a red heat, after which the cooling rate may be increased although it must still be kept lower than would result 30 from removal of the material from the furnace. The cooling may often be permissible at an increasing rate with the material in the furnace down to a certain point, depending upon the characteristics of the material, 35 when the charge may be removed from the furnace and allowed to cool in the open air.

In carrying out our invention we provide cooling means for the furnace whereby the desired rates of cooling may be obtained comprising cooling ducts in the furnace through 40 which air is forced during one period of the cooling cycle, and apertures which may be opened to provide for circulation of the outside air directly through the furnace during 45 another portion of the cooling cycle, after which the charge may be removed.

For a more complete understanding of our invention reference should be had to the accompanying drawing, Fig. 1 of which is a 50 view partially in section, of an electric fur-

nace embodying our invention; Fig. 2 is a diagrammatic view showing details of construction, while Fig. 3 shows curves illustrating typical cooling cycles.

Referring to the drawing, we have shown 55 our invention in one form in connection with an electrically heated furnace although it will be understood that various other suitable forms of heat may be used. In the form shown the furnace comprises suitable heat refractory walls 10 surrounded by a metallic supporting framework 11. This framework also carries suitable means (not shown) for raising and lowering a door 12 at one end of the furnace. The bottom of this furnace on which the charge is placed on hearth plates 13 is mounted on wheels 14 which run on tracks 15 and 16 whereby when the door is lifted the bottom, which is in the form of a car, can be run out of the furnace on the 60 tracks to facilitate loading and unloading of the charge. As shown, the car may be moved into and out of the furnace by means of a stationary gear 17 mounted below the car and engaging with a rack 18 carried by 65 the car. The gear may be turned through a shaft 19 and a reduction gearing 20 through which connection is made to a suitable electric driving motor, not shown. Suitable electric heating resistors 21 are mounted on heat 70 refractory insulating supports secured to the wall of the furnace.

To provide forced cooling during one portion of the cooling cycle we have provided a plurality of cooling pipes 22 extending transversely across the interior of the furnace at the top thereof. As shown each pipe has a vertical portion at each end extending upward through the furnace wall to the exterior. One end of each of the pipes has free access 80 to the outside air while the other ends of the pipes are connected to a conduit 23 extending lengthwise of the furnace. This conduit is also connected to a suitable air blower 24 (Fig. 2). Thus by turning on the blower, cooling air may be forced through the plurality of cooling ducts 22 to thereby extract 85 heat from the furnace. It will be observed that the pipes form cooling paths closed off from the furnace chamber. The tubes are 90 95 100

made of suitable heat resisting material such as an alloy of nickel and chromium or an alloy of nickel, chromium and iron.

For another step in the cooling cycle provision is made for the opening of the furnace to allow a limited amount of air to circulate directly through the heating chamber to give a still higher cooling rate. As shown, a plurality of ducts 25 are provided in the wall 10 of the furnace at the bottom, each of these ducts terminating on the exterior of the furnace in an upwardly extending portion 26 which may be closed by a cover 27. Preferably, the cover is sealed by providing it with 15 a flange 28 which, when the cover is closed, enters a suitable liquid 29, such as oil, contained in a trough 30 surrounding the upper end of the duct portion 26.

In the roof of the furnace a plurality of 20 vertical ducts 31 are provided, these ducts being preferably arranged centrally of the roof and spaced apart from the front to the back. Each of these ducts is provided with a sand sealed cover 32 similar in construction 25 to the cover 27.

Preferably the covers 27 and 32 are raised and lowered simultaneously to open and close the apertures. As shown, this may be done by means of a handwheel 33 driving a worm 34 which cooperates with a wormwheel 35. Connected to a crank 36 operated by the wormwheel is a link 37 which in turn is connected to a crank 38 secured to a shaft 39 mounted on the furnace and running from the front to the back of the furnace. A similar shaft 40 is mounted on the opposite side of the furnace and connected to the shaft 39 through suitable cranks and a link 41 so that the two shafts may be rotated together by 35 turning the wormwheel 35. Each of the covers 27 is connected to one of these shafts through a link 42 and a crank 43 connected to the shaft, the covers on a given side of the furnace being, of course, all connected to the 40 same shaft.

For the operation of the covers 32, a central shaft 45 is provided just above these covers and extending from the front to the rear of the furnace. Each of the covers is secured to a sheave 46 secured in turn to the shaft 45, the connection between the cover 32 and the sheave being effected by a flexible member 47 such as a metallic cable. The shaft 45 is connected to the shaft 39 through 50 suitable cranks and a link 48 so that when the shaft 39 is turned the shaft 45 and with it the sheaves 46 are turned to raise or lower the covers 32. It will thus be observed that by turning the handwheel 33 all the covers 55 may be simultaneously raised and lowered.

In the operation of the furnace after the charge has been suitably heated the electric current or other source of heat is turned off and the furnace allowed to cool. For example, in the annealing of a charge of steel the

temperature, as shown in Fig. 3, may be increased to about 1475° Fahr. The furnace may then be shut down, that is, the source of heat turned off and allowed to cool while closed, at its natural rate, no forced or artificial cooling being used. This rate will be determined by the heat insulating characteristics of the furnace walls 10. 70

After the furnace has cooled down to a predetermined temperature, for example, about 1200° Fahr. at which the rate of cooling may be safely increased, the blower 24 may be turned on to force air through the cooling tubes 22. Preferably, the diameter of the conduit 23 is gradually decreased, as shown 80 in Fig. 2, from the end connected to the blower to the opposite closed end in order to provide for a uniform air pressure throughout the length of the duct and consequent uniform air flow through the cooling tubes 22. 85

After the forced cooling by means of the tubes 22 has been continued for a time, such as several hours, sufficient to reduce the charge to a predetermined temperature, such as 800° Fahr., permitting a sheltered exposure of the charge to the air and at which a higher rate of cooling may be used without detrimental effect upon the material, the blower 24 is preferably shut down although it may still be used if desired, and the handwheel 33 operated to raise the covers 27 and 32 to allow a natural draft circulation of the outside air through the heating chamber. This air enters through the ducts 26 at the bottom and passes out at the top through the ducts 31. This cooling will be continued for a predetermined period or until the temperature of the charge has dropped to a value at which it may be exposed to the outside air. The furnace may then be opened and the charge 100 taken out. 105

It will be observed that we have provided a very flexible control means for the cooling cycle. The natural cooling period and the forced cooling period may be varied as desired. Furthermore, where the conditions are suitable the furnace may be cooled rapidly immediately after being shut down by starting the blower. In the cooling cycle shown by curve A, Fig. 3, the natural rate of cooling is continued for about 12½ hours until the material has been cooled down to somewhat less than 1200° after which the blower is started and used for a period of about 6½ hours to cool the material down to somewhat less than 800°. The covers 27 and 32 are then raised to accelerate the cooling rate so that the furnace temperature after about 5 hours has been reduced to around 400°. The charge may then be removed from the furnace and further cooled in the outside air. It will be understood, of course, that this curve represents the temperatures in the heating chamber of the furnace and likewise the temper- 110 115 120 125

atures of the outer service portions of the charge. The temperature of the interior of the charge may be somewhat higher depending upon its size and the accessibility of its 5 various portions to the furnace atmosphere.

In Fig. 3 the lower portion B of the curve indicates a cooling cycle wherein the blower was turned on after about $6\frac{1}{2}$ hours of natural cooling, the blower being used for about 10 the same length of time to cool down to about 800° after which the covers 27 and 28 were lifted to accelerate the cooling. This provides a shorter cooling cycle.

What we claim as new and desire to secure 15 by Letters Patent of the United States, is:

1. A furnace comprising walls forming a heating chamber, cooling ducts extending through at least one of said walls into said chamber giving a predetermined rate of cooling and means providing a limited circulation of air through the furnace to give a 20 higher rate of cooling.

2. A furnace comprising walls forming a heating chamber, heating means for said 25 chamber, a plurality of ducts extending through said chamber, means for forcing a cooling fluid through said ducts to cool the chamber at a predetermined rate, said walls being provided with apertures in upper and 30 lower regions for giving a limited circulation of air through said chamber for a more rapid rate of cooling and closure means for said apertures.

3. A furnace comprising walls forming a 35 heating chamber, heating means for said chamber, a plurality of ducts extending through said chamber, means for forcing a cooling fluid through said ducts, said walls being provided with apertures in upper and 40 lower regions for giving a limited circulation of air through said chamber, closure means for said apertures and means for operating said closure means to control the flow of air through said apertures.

4. A furnace comprising walls forming a heating chamber, heating means for said 45 chamber, said walls being provided with a plurality of apertures in respectively upper and lower regions of said chamber whereby 50 a limited circulation of outside air through said heating chamber may be obtained, a closure device for each of said apertures and operating means connected with said closure devices for effecting simultaneous opening or 55 closing movement thereof.

5. A furnace comprising a plurality of side and roof walls forming a heating chamber, 60 said roof walls being provided with a plurality of apertures and at least two opposite side walls being provided with a plurality of apertures communicating with a lower region of said chamber whereby a circulation of cooling air through said chamber may be produced, closure means for said apertures, a 65 shaft mounted on each of said opposite side

walls above said side wall openings, means for turning said shafts simultaneously and connections between said shafts and said closure means.

6. The method of cooling a charge in a 70 furnace provided with closed path cooling means and also with means providing for limited circulation of air through the furnace which consists in allowing the furnace to cool at its natural rate down to a predetermined temperature, cooling at a greater rate by said closed path cooling means down to a temperature suitable to a sheltered exposure to air, then admitting air to provide for an increased rate of cooling down to a 80 predetermined temperature and thereafter removing the charge from the furnace and allowing it to cool in the outside air.

7. A furnace comprising walls forming a 85 heating chamber, cooling ducts extending through at least one of said walls into said chamber, means for forcing a cooling fluid through said ducts to cool the chamber at a predetermined low rate, said walls being provided with ventilating apertures for effecting a circulation of outside air through said chamber for a higher rate of cooling, and closure means for said apertures.

In witness whereof we have hereunto set 90 our hands.
